LOUDEN A. McCOURBIE AND CHARLES F. RAYDURE, OF PHILADELPHIA,
PENNSYLVANIA.

SHOE FOR THIRD-RAIL ELECTRIC CARS.

1,009,767.

Specification of Letters Patent. Patented Nov. 28, 1911.

Original application filed April 24, 1909, Serial No. 492,017. Divided and this application filed October 22, 1910. Serial No. 588,450.

To all whom it may concern:

Be it known that we, LOUDEN A. McCOURBIE and CHARLES F. RAYDURE, both citizens of the United States, residing at the 5 city of Philadelphia, in the county of Philadelphia and State of Pennsylvania, have jointly invented certain new and useful Improvements in Shoes for Third-Rail Electric Cars, of which the following is a specification.

Our present invention has relation to a 10 shoe with a removable contact-piece for third-rail electric railway cars embodying improvements over Letters Patent No. 985,430, dated February 28th, 1911, granted to us and of which this application is a division 15 of the application filed April 24th, 1909, for the said patent; the present application having reference to constructive details in the 20 arrangement of such a shoe, for the above defined purpose.

Our invention will be more fully understood from the following description taken 25 in connection with the accompanying drawings forming part hereof, in which—

Figure 1, is a top or plan view of a third-rail shoe with a removable upper rail contact; the said view embracing main features of our present invention. Fig. 2 is a front 30 elevational view of the same. Fig. 3, is a vertical central sectional view on the line α , α , of Fig. 2, with the electrical connections omitted; and Fig. 4, is an end elevational view of the shoe-member showing in detail 35 the removable upper rail contact-piece.

In the drawings a , is a shoe or contact-member and a^1 , a supporting-member to which the shoe or contact-member is pivotally attached. These members are arranged so as 40 to be adjustably secured to a plate a^5 , forming part of a car-truck frame, not shown.

The shoe-member a , has a central perforated tubular part arranged to provide a bearing to fit between two end perforated 45 tubular parts of said supporting member a^1 . Formed with the central portion of the shoe-member a is a tapering projection a^9 as clearly illustrated in Figs. 3 and 4, to be presently described. Through the perforated tubular parts of both members a and 50 a^1 , is inserted a pin a^2 , to form a pivotal connection for the same, as clearly shown in Figs. 1 and 3. The respective ends of the pivot-pin a^2 , have openings to receive

cotter-pins a^3 and a^4 , so that when the cotter- 55 pins are removed the pivot-pin a^2 , may be readily withdrawn and the shoe-member a , released from the supporting member a^1 . The member a^1 , is preferably arranged with an upper rear ratcheted surface Fig. 3, to 60 register with a ratcheted plate a^5 , intended to be secured to the car-truck frame.

The ratcheted surface of the member a^1 by registering with the ratcheted plate a^5 , insures the two to be adjustably secured in 65 required operative position and so held then by tightening bolts a^6 and a^7 , as clearly shown in Fig. 2, whereby when required the shoe-member a may be quickly and securely brought into proper operative relation with 70 an electrified rail of a road-bed, not shown. The shoe-member a , is recessed in the front portion to receive the rail shoe or contact-piece a^8 , held by means of removable bolts. As shown the shoe or contact-piece a^8 , is 75 beveled off adjacent to the respective edges, as clearly shown in Fig. 1.

The supporting member a^1 , is provided with a blocklike casting b , having a vertical opening b^1 and a chamber b^7 , provided 80 therein. b^2 is a headed bolt partially threaded and vertically extending through the opening b^1 and through an opening in the shoe-member a , as shown in Fig. 3. On the threaded portion b^4 of the bolt b^2 is 85 applied a nut b^3 to permit in a handy manner the compressing of a coiled spring which encircles the bolt b^2 and engages a seating-cap b^6 , to be presently more fully explained. In case of wear of the contact a^8 , the nut 90 b^3 and bolt b^2 , provide by manual turnings of the nut on the said bolt through the compressing of the coiled spring b^5 to take up such wear. The bolt b^2 , carrying at the upper end the seating-cap b^6 , and against 95 which at one end engages the helical spring b^5 , and at the other end the spring has a bearing in a recess b^8 of the member a^1 , to maintain normally the shoe-member a , under required spring tension with the supporting member a^1 , to establish and maintain 100 reliable surface contact of the shoe-member a , with an electrified rail. The tapering projection a^9 , of the member a extends upward into the chamber b^7 , of the member a^1 and this chamber is of greater 105 width than the projection. The bottom surface of the supporting member a^1 , is shaped

so as to contact with the outer surface of the tubular part on both sides of the chamber b^7 , as clearly shown in Fig. 3. By this arrangement wear of the bottom surface of 5 the supporting member a^1 against the tubular part of the member a and pivot-pin a^2 , in the tubular parts of both members will be equalized so that both members have two 10 real points of bearing contact to insure greater uniformity of action of the shoe-member in contact with a live rail and also far more reliable practical results are obtained during such contact. When the contact 15 piece a^8 , has become worn by turning the nut b^3 , on the threaded portion of the bolt b^2 , within certain limits this is provided for, that is, to the extent of normal movement of the projection a^9 , of the contact-member a , within the chamber b^7 , of the supporting 20 member a^1 , without having to disarrange other parts of either member to accomplish such result.

e and e^1 , are insulated electric wire connections of the shoe-member a . These wires 25 are detachably connected with binding posts d and d^1 and e and e^1 , of a plate e , suitably bolted to the upper portion of the supporting member a^1 , as illustrated in Figs. 1, 2 and 4.

Having thus described the nature and

object of our invention, what we claim as new and desire to secure by Letters Patent is:—

A shoe for electric-railway cars, comprising a horizontal shoe-member provided with 35 a contact piece and a tubular-part having a vertical tapering projection, a vertical supporting member provided with a chamber into which extends said projection and the chamber of said supporting member of 40 greater width than said projection and the bottom surface of said supporting-member shaped to contact with the outer surface of said tubular part on both sides of said chamber, a pivot extending through said tubular- 45 part and connecting said shoe-member with said supporting-member, means arranged in front of said pivotal connection for maintaining under working tension said members and electrical-connections for the contact-piece of said shoe-member.

In witness whereof, we have hereunto set our signatures in the presence of two subscribing witnesses.

LOUDEN A. McCOURBIE.
CHARLES F. RAYDURE.
